SANITARY FLUSHLESS TOILET

Henry G. Yamada, Piedmont, and George Y. Yamada, Oakland, Calif.

Application January 29, 1951, Serial No. 208,392

1 Claim. (Cl. 4—128)

1

This invention relates to improvements in flushless toilets of the character employed outside or inside of buildings and has for the primary object the provision of a specially constructed mechanism for opening and closing the door or trap covering the toilet pit that is associated with the toilet proper.

One of the objects of the present invention is the provision of a means adapted to be operated by the feet of the user of the toilet for automatically opening and closing the door covering the toilet pit.

Another object of the present invention is the provision of a combined lever and gearing mechanism for automatically controlling the door covering the pit.

A further object of the present invention is to provide an improved vent associated with the pit and door outlet for venting the pit.

A still further object of the present invention is the provision of an elongated upwardly extending flue in communication with the pit for venting the same and to provide a suction fan in the flue for automatically drawing the fumes from the pit.

A still further object of the present invention is the provision of an outside flushless toilet that is sanitary, simple in construction, economical to manufacture and highly efficient and serviceable in use.

Other objects and advantages will be apparent during the course of the following description.

In the accompanying drawings forming a part of the specification, wherein for the purpose of illustration like numerals designate like parts throughout the same,

Fig. 1 is a top plan view of the improved toilet,
Fig. 2 is a central vertical sectional view of the same,

Fig. 3 is a side elevational view of the toilet,
Fig. 4 is a vertical sectional view taken on line 4—4 of Fig. 3 looking in the direction of the arrows, and

Fig. 5 is an end elevational view of the device, for the purpose of clarity the foot lever and foot gear being removed.

Referring in detail to the drawings and the numerals thereof, wherein for the purpose of illustration like numerals designate like parts throughout the same, the numeral 7 designates the toilet bowl as a whole and the numeral 8 the seat thereof, which seat is apertured as at 9 for the passage therethrough of human excretion. An outlet 10 leads downwardly from the bowl to a conventional pit, not shown, and a downwardly extending urine receiving trough 11 leads to and within the front portion of the bowl as disclosed to advantage in Fig. 2. A horizontal door 12 is positioned beneath the trough 11 and covers the said outlet and is pivotally secured to the body of the outlet as at 13. The numeral 14 designates a suitable stop for retaining the door in a horizontal position as disclosed to advantage in Fig. 2.

2

A gear member 15 is formed on the outer extremity of the door 12 and engages an idler gear 16, which idler gear is engaged by the drive gear 17. A substantially horizontal shaft 18 is fixed to the said drive gear 17, which shaft 18 is fixed to a foot lever 19 of substantial width.

It is obvious, when a user of the toilet stands or otherwise exerts a downward pressure on the said foot lever 19, the gearing mechanism associated therewith will cause the swinging door 12 to automatically open as shown in dot and dash lines in Fig. 2, whereby the bottom outlet 10 will be open for receiving urine from the user of the chute 11. Thus when the said foot lever 19 is pressed downwardly the swinging door 12 will automatically open. A conventional upwardly extending vent 20 projects from the rear portion of the toilet bowl 7 and communicates therewith through the vent opening 21, whereby all odors from the bowl and toilet outlet are conveyed therefrom. A conventional electrically operated suction fan or blower 22 is associated with said vent to assist in quickly carrying off the odors. A suitable electric conductor 23 controlled by an electric switch 24 and operated by the foot lever 19 is provided for controlling the operation of the blower. Thus when foot pressure is exerted on the lever 19 to raise the door 12, the blower is automatically operated for venting the toilet bowl 7. The blower can be a windmill, if desired.

It is to be understood that the form of my invention herewith shown and described is to be taken as a preferred example of the same and that various changes relative to the shape, size, material and arrangement of parts may be resorted to without departing from the spirit of the invention or the scope of the subjoined claim.

Having thus described our invention, we claim:

A toilet structure comprising a housing, an apertured seat on the upper portion thereof, an inclined trough extending in front of and beneath the seat and leading to and within the housing, said housing having a downwardly extending passageway, a hingedly secured cover closing said passageway, means including a gearing mechanism for opening said cover, said means including a foot lever, and a mechanism including a plurality of gears associated with the foot lever and door.
